MUSICAL INSTRUMENT

Jasper Karl Mason, Warner, N. H.

Application February 24, 1947, Serial No. 730,361

8 Claims. (Cl. 84—382)

1

This invention relates to musical instruments and pertains more particularly to an improved wind instrument in the nature of a clarinet having key-operated valve for opening or closing a plurality of tone holes.

The principal purpose of the invention is to provide a clarinet or similar instrument with improved means, herein designated as "tracker mechanism," connecting the keys with the respective tone hole valves, in such a manner that the keyboard may be composed entirely of keys and with no finger holes to cover and may be consolidated for convenient operation by the musician, regardless of the location of the tone holes and their control valves. An instrument equipped with the novel tracker mechanism may thus be designed to afford optimum musical range and quality without sacrifice of ease and simplicity of fingering, for the keys may be compactly located in such relative positions as best suits the convenience of the operator, while the tone holes may be disposed along the length and periphery of the wind tube at such positions as dictated by the pitch and musical compass of the instrument without limitation as to facility or convenience in the matter of fingering.

Heretofore, such wind instruments have been equipped with tone holes to be closed by the fingers and with keys connected by levers or bars of various lengths and designs with the tone hole valves of the instrument and hence engendering mechanical complexity and noisy operation. In low pitched instruments, for example, the necessary spacing between the tone holes is particularly wide and the valve keys for the lower registers to be brought into positions convenient to the finger reach of the operator require the introduction of extended mechanisms whose design adds undesirable weight to the instrument.

These objections and inconveniences are obviated by providing a compact instrument equipped with a series of tracker rods or slides for operating the valves, and the keyboard of the improved instrument may be arranged with full regard to convenience of fingering, whether the operator's hand be large or small, and in such order of fingering as to accord with accepted methods. The wind tube may be of such length and contour as to afford the musical compass required, without complicating the operating mechanism or the general design of the instrument.

Additional features and advantages of the improved wind instrument will be apparent from the following description of a recommended embodiment of the invention as shown on the ac-

2

companying drawings, and will be pointed out in the appended claims. It will be understood, however, that the novel clarinet herein shown and described is merely illustrative of one type of wind instrument which may be equipped with the improved tracker mechanism, and that the design or structural details of the instrument as a whole may be varied within wide limits without departing from the essence of this invention as set forth in the claims.

In the drawings,

Fig. 1 is a plan view of a four-octave bass clarinet provided with my improved tracker mechanism and keyboard;

Fig. 2 is a side view of the instrument looking to the right of Fig. 1;

Fig. 3 is an enlarged diagrammatic, transverse section showing an arrangement of the slides or rods of the tracker mechanism with relation to the reversely bent tube between the courses of which the mechanism is located in the form here illustrated;

Fig. 4 is an enlarged diagrammatic transverse section showing the operative connection between a valve and tracker rod, certain parts beyond the plane of section being omitted;

Fig. 5 is a broken diagrammatic side view, illustrating in simplified form typical valves and corresponding keys of the instrument, and the tracker mechanism for actuating the valves;

Fig. 6 is a view similar to Fig. 5 and taken on line 6—6 of that figure; and

Fig. 7 is a diagrammatic sectional perspective view showing an arrangement of bridge members for guiding twenty tracker rods in four banks of five rods each.

In the particular embodiment of the invention chosen for the purpose of illustration, an "A-foot" bass clarinet is designed to afford a total range of four octaves, and provides twenty tone holes with twenty keys for actuating the twenty valves for the respective tone holes together with two "register" holes for production of the twelfths of the prime tones. It will be appreciated that such an instrument not only illustrates the flexibility of the tracker mechanism which connects the several keys with the several valves, and its adaptability to an instrument having a large number of tone holes, but also introduces a new type of clarinet capable of development to an effective range even greater than that of the illustrated instrument.

As here shown, the portion of the tube near the mouthpiece provides a straight section for the compact, consolidated keyboard; the balance of

the tube is S-shaped, provided with three parallel courses between the keyboard section and the bell; and the tracker mechanism is mounted on top of the keyboard section of the tube and extends between two of said parallel courses. It is apparent that the tube may have more or fewer bends and tone holes than in the form illustrated, or that it may be straight throughout its length when the musical compass of the instrument does not render the straight tube too long for convenient or practical use.

An important factor in the conception and design of an instrument equipped with a tracker mechanism such as herein described is embodied in the facility of construction engendered by the respective and related placements of tone holes and keyboard, the former being located in the sides of the instrument, the latter along the top of the keyboard section of the tube; this arrangement making possible the free operation of respective valves without interference with the mechanism of other valves; the tracker rods in the illustrative instrument here described being arranged in four banks of five rods each, the two inside banks being of rods extending into the tone hole courses of the instrument further than do the rods of the two outside banks, thus enabling freedom in the matter of connecting mechanisms between the rods and tone hole valves; and the extension upward into the keyboard of the rods in each of the four banks increasing progressively from top rod to bottom rod, thereby permitting freedom in the matter of connections between tracker rods and their respective keys. In addition, the arrangement of tracker rods thusly in parallel banks permits the simultaneous multiple operation of two or more valves by depression of a single key or the operation of a selected valve from more than one key.

It will be understood that while the illustrated instrument shows the tone holes as located within the courses of the reversely bent section of the tube, this is not to be regarded as a limitation to design; if desirable, the placement of tone holes may be extended upward into the keyboard section of the tube or downward by extending the length of the tube to whatever limits may be demanded by the required musical compass.

It will also be understood that the diameter of the tube and the size and spacing of the tone holes, as well as the length of the tube and number of tone holes to be provided, depend upon the desired range and pitch of the instrument and are determined from calculations based upon experience or mathematical tables, within the limits of musical accuracy. I have found that the instrument herein described will perform satisfactorily when made from a tube having a uniform bore of approximately seven-tenths (0.70) inch and an outside diameter of approximately seventy-five hundredths (0.75) inch, and when the tone holes are sized by a graduated sequence in four equal groups of five tone holes each with a uniform tone hole diameter for each group. For example, the five tone holes for the lowest pitched notes may have a diameter of $10/16$ "; the five succeeding higher pitched holes are then $9/16$ " in diameter; the next five are $8/16$ "; and the highest pitched five tone holes are $7/16$ " in diameter. Such grouping of the tone hole sizes facilitates manufacture of the wind tube without noticeable impairment of musical pitch or quality; but the diameters of the tube may be larger or smaller and the tone holes

may obviously be graduated in size, individually, if desired, and of such larger or smaller diameter as may be required by the particular musical compass selected for design.

5 As shown in Figs. 1 to 4, the complete instrument comprises the wind tube 11 having a keyboard section 12 adjacent the mouth piece 13, and a looped section 14 adjacent the bellend 15. A frame 16 is mounted on the keyboard section 10 of the tube and a plurality of keys 17 are suitably pivoted in the frame to provide a keyboard assembly. The looped or S-shaped section of the tube includes parallel courses 18, 19 and 20, and the tone holes 21 and their control valves 22 are located in or on these courses of the reversely bent tube. The tone hole openings and the valves are of conventional structure, the cupped valves having the customary pads which seat over the rims of the tone holes. The mouthpiece 13 may be a conventional clarinet mouthpiece, modified if necessary by altering its bore to correspond with the bore of the wind tube, or of such other design as may be required for acceptable tone quality.

25 The novel tracker mechanism interconnecting the keys with corresponding valves comprises a plurality of sliding bars, rods, wires or the like, extending through the carriage 16 and into the space between the courses 18 and 19 of the wind tube. As here shown, these slides or rods 23 consist of relatively wide and thin metal strips and are arranged to be pulled by the key levers in actuating the valves.

35 The lever arms 24 of the keys 17 are suitably mounted on pivot shafts 25 pivoted at 26 in the sides of the frame 16; and the ends of the arms 24 are suitably joined to the ends of the respective slides 23, preferably by a pivot joint 27, as best shown in Figs. 5 and 6. Depression of the 40 keys swings the lever arms to retract the slides, as aforesaid.

As also best shown in Figs. 5 and 6, the valve cups 22 are connected by arms 28 to pivot shafts 29 pivoted in bosses 30 soldered or otherwise 45 affixed to the tube courses 18 and 19; and the shafts 29 are linked to complementary slides of the tracker mechanism, so that retraction of a slide will actuate a selected valve, either to open or 50 close the tone hole. It will be understood that some of the keys of the instrument are arranged, on depression, to open respective valves, while 55 depression of other keys closes respective valves; and it will be appreciated that the location of the valves on the pivot shafts and the character of the linkages between the shafts and the corresponding slides may vary according to the position and nature of the tone hole to be opened or closed.

Three typical installations are illustrated in 60 Figs. 5 and 6. The valve 22a is normally closed and is disposed to the right of its pivot shaft 29a. The valve 22b is normally open and is disposed at the left of its shaft 29b. Both of these shafts may thus be connected to their respective slides by a simple linkage comprising an offset link 31 65 preferably connected at 32 to a short arm 33 fixed to the appropriate slide 23. Retraction of an associated slide thus opens valve 22a or closes valve 22b.

70 Because of the location of the normally closed valve 22c, an auxiliary actuating shaft 34 is disposed parallel to the valve shaft 29c, the two shafts having complementary projecting rocker arms 55 and 56, respectively, normally in engagement, so that upon rotation of the auxiliary shaft

34 in a counter-clockwise direction (as viewed in Fig. 6) the arm 55 of shaft 34 depresses the arm 56 of shaft 29c, causing the latter to rotate in the opposite direction to open the valve 22c. The auxiliary shaft is connected to the slide 23c by link 31 and arm 33, in the same manner as the shafts 29a and 29b.

Each valve is held in its normal position by a spring 35 fixed in one of the shaft-supporting bosses 30 and engaging a catch 36 on the shaft, as best shown in Fig. 4. Other types and arrangements of resilient means for restoring the valves to normal position may be utilized to suit the convenience of the manufacturer.

The slides 23 of the tracker mechanism are preferably guided by bridge members extending between the tube courses 18 and 19, and disposed on the keyboard section 12 of the tube, if desired. As shown in Fig. 3, these bridges may comprise a central block or comb member 37 having slots in its opposite sides to receive the respective slides 23, and removable side members 38 having complementary slots in their inner faces. The side pieces 38 have ends shaped to fit against the tube courses 18 and 19 and are removably held in position against the tubes and in proper relation to the center piece 37, by screws 39.

The tracker rods or slides are preferably arranged in multiple banks, as previously explained, and the bridge members are designed to accommodate the number of rods necessary to operate the valves required by the instrument. The arrangement shown in Figs. 3 and 4 is merely illustrative of an installation accommodating ten tracker rods in two parallel banks of five rods each. The arrangement shown in Fig. 7 is illustrative of a bridge member accommodating twenty tracker rods in four banks of five rods each.

In Fig. 7, the bridge comprises top and bottom members 40 and 41 shaped to fit the respective tube courses 18 and 19; a center post 42 which slidably fits between the members 40 and 41; two comb members 43 and 44 which also slidably fit between the members 40 and 41 on opposite sides of the center post 42 and which have recesses 45 on their opposite sides to provide guide slots for the twenty tracker rods; and side members 46 which fit against the respective tube courses and are fastened by screws or otherwise to the members 40 and 41, to retain the center post and comb members in operative position. It will be apparent that removal of the side members or retaining plates 46 permits the removal of the double comb members 43 and 44 and the center post 42.

The springs associated with each valve shaft tend to hold the valves and keys in inoperative position and to draw the tracker slides away from the keyboard assembly. The movement of the rods under such spring tension is preferably limited by stops disposed on the slides or on the valve arms. As shown in Fig. 6, the slide 23c carries a stop member 47 engaging a bridge block 37; and the arm 28 of valve 22b has an extension stop 48 engaging the surface of the tube 19.

It will be appreciated, as aforesaid, that the structural details of the improved instrument are shown more or less diagrammatically, particularly in Figs. 3 to 6, in which many of the slides necessary to the operation of a clarinet have been omitted from the views for the sake of clarity. Moreover, these structural details may be modified to suit particular conditions or types of instruments without departing from the

essence of this invention as defined in the following claims.

I claim:

1. A musical instrument of the character described, comprising a wind tube having a plurality of longitudinally spaced tone holes, a keyboard assembly mounted adjacent and parallel to one end of the tube and having a plurality of keys pivoted therein and spaced longitudinally of said tube, movable valves pivotally mounted on the tube for controlling the respective tone holes, and tracker mechanism extending longitudinally of the tube for operation of a corresponding valve upon manual depression of a selected key irrespective of the distance between said valve and key, said tracker mechanism comprising longitudinally slidable rods extending parallel to said tube along one side thereof, and means connecting the several rods to their respective several keys and to their corresponding valves.

2. A musical instrument of the character described, comprising a wind tube having a plurality of longitudinally spaced tone holes, a keyboard assembly mounted adjacent and parallel to one end of the tube and having a plurality of keys pivoted therein and spaced longitudinally of said tube, movable valves pivotally mounted on the tube for controlling the respective tone holes, and tracker mechanism extending longitudinally of the tube for operation of a corresponding valve upon manual depression of a selected key irrespective of the distance between said valve and key, said tracker mechanism comprising longitudinally slidable rods extending parallel to said tube along one side thereof, and means connecting the several rods to their respective several keys and to their corresponding valves, and bridge members mounted on the tube in longitudinally spaced relation and having openings receiving

40 said rods for guiding sliding movement thereof.

3. A musical instrument of the character described, comprising a wind tube having a plurality of longitudinally spaced tone holes, a keyboard assembly mounted adjacent and parallel to one end of the tube and having a plurality of keys pivoted therein and spaced longitudinally of said tube, movable valves pivotally mounted on the tube for controlling the respective tone holes, and tracker mechanism extending longitudinally of the tube for operation of a corresponding valve upon manual depression of a selected key irrespective of the distance between said valve and key, said tracker mechanism comprising longitudinally slidable rods extending parallel to said tube along one side thereof, and means connecting the several rods to their respective several keys and to their corresponding valves, bridge members mounted on the tube in longitudinally spaced relation and having openings receiving

45 said rods for guiding sliding movement thereof, and springs associated with said valves and holding them in inactive position, certain of said rods having stop members engageable with a bridge member to limit the movement of said rods under action of said springs.

4. A musical instrument of the character described, comprising a tube bent upon itself to provide parallel courses and a keyboard extension at the mouthpiece end of the tube, longitudinally spaced tone holes in each of said courses, valves pivotally mounted on said courses for controlling the tone holes, keys pivotally mounted on said extension in longitudinally spaced relation, and tracker mechanism interconnecting corresponding keys and valves, said tracker mecha-

nism comprising longitudinally movable rods disposed between and extending parallel to said tube courses and along the keyboard extension, and means connecting each rod to a key and to a corresponding valve, whereby depression of a key moves one of the rods and actuates the corresponding valve.

5. A musical instrument of the character described, comprising a tube bent upon itself to provide parallel courses and a keyboard extension at the mouthpiece end of the tube, longitudinally spaced tone holes in each of said courses, valves pivotally mounted on said courses for controlling the tone holes, keys pivotally mounted on said extension in longitudinally spaced relation, tracker mechanism interconnecting corresponding keys and valves, said tracker mechanism comprising longitudinally slidable rods disposed between and extending parallel to said tube courses and along the keyboard extension, and means connecting each rod to a key and to a corresponding valve, and a bridge member transversely mounted between said courses, said member having openings receiving said rods for guiding sliding movement thereof.

6. A musical instrument of the character described, comprising a tube bent upon itself to provide parallel courses and a keyboard extension at the mouthpiece end of the tube, longitudinally spaced tone holes in each of said courses, valves pivotally mounted on said courses for controlling the tone holes, keys pivotally mounted on said extension in longitudinally spaced relation, tracker mechanism interconnecting corresponding keys and valves, said tracker mechanism comprising longitudinally slidable rods disposed between and extending parallel to said tube courses and along the keyboard extension, and means connecting each rod to a key and to a corresponding valve, and spaced bridge members removably attached to the tube between said courses, said members having transversely spaced slots receiving the respective rods for guiding sliding movement thereof.

7. A musical instrument of the character described, comprising a tube bent upon itself to provide parallel courses and a keyboard extension at the mouthpiece end of the tube, longitudinally spaced tone holes in each of said

courses, valves pivotally mounted on said courses for controlling the tone holes, keys pivotally mounted on said extension in longitudinally spaced relation, tracker mechanism comprising flat, slidable rods interconnecting corresponding keys and valves and extending between said courses and parallel thereto, and a series of bridge members transversely mounted between said courses and each comprising a guide member having slots in its opposite sides for receiving the respective rods, and a side piece removably attached on the outer side of said guide member to close said slots and retain the rods therein, whereby sliding movement of the rods is guided by said bridge members.

10 8. A musical instrument of the character described, comprising a tube bent upon itself to provide parallel courses and a keyboard extension at the mouthpiece end of the tube, longitudinally spaced tone holes in each of said courses, valves pivotally mounted on said courses for controlling the tone holes, a keyboard frame mounted on said keyboard extension parallel thereto, keys pivoted to said frame in longitudinally spaced relation, tracker mechanism comprising flat, slidable rods interconnecting corresponding keys and valves and extending between said courses and parallel thereto, and a series of bridge members transversely mounted between said courses and 15 between the keyboard frame and the instrument tube and each comprising guide members having openings arranged for receiving the respective rods, a center post, and side pieces removably attached on the outer sides of said guide members 20 to retain the said guide members and center post 25 and to retain the rods therein.
